To all whom it may concern:

Be it known that I, Victor Nemeroff, a citizen of the United States, residing at Chicago, in the county of Cook and State of Illinois, have invented a new, original, and ornamental Design
for a Lamp Shade, of which the following is a specification, reference being had to the accompanying drawings forming part thereof.

Fig. 1 is a front perspective view of a lamp
shade showing my new design;

Fig. 2 is a front elevational view of the same;
and

Fig. 3 is an end elevational view thereof.

I claim:

The ornamental design for a lamp shade as shown.

VICTOR NEMEROFF.
